UNITED STATES PATENT OFFICE.

FRANK GODDARD, OF LONDON, ENGLAND.

HAMMOCK.

1,400,049.

Specification of Letters Patent. Patented Dec. 13, 1921.

Application filed May 13, 1921. Serial No. 469,365.

To all whom it may concern:

Be it known that I, FRANK GODDARD, a subject of the King of Great Britain, residing at London, England, have invented a new and useful Hammock, (for which I have filed applications for patents in the following countries: Great Britain, 21562, October 27, 1914; France, 506,370, November 19, 1919; Germany, January 9, 1920; Austria, January 23, 1920; Czecho-Slovakia, February 13, 1920; Japan, July 15, 1920; Australia, August 16, 1920; Argentina, October 28, 1920; Brazil, October 29, 1920; Canada, October 30, 1920, and Belgium, June 4, 1920,) of which the following is a specification.

This invention relates to improvements in portable sleeping apparatus of the collapsible type and consists essentially of a skeleton framework capable of being readily dismounted and put together again and of supporting without struts, stays, ties and the like, a hammock-like receptacle adapted to be supported from transverse members at the ends of such framework. A further feature of the invention consists in the provision of suitable means for supporting a canopy, mosquito curtain, rainproof cover or the like. Means are also provided for quickly and readily attaching wheels to the framework to serve as a light ambulance or portable bed.

In the accompanying drawings:-

Figure 1 is a perspective view of my improved apparatus.

Figs. 2 and 3 are side elevation and plan view of the frame ready for the hammock-like receptacle to be attached thereto.

Fig. 4 is a perspective view, to an enlarged scale, showing the method of securing the hammock-like receptacle to the frame.

Fig. 5 shows a perspective view of one end of the hammock, showing the means employed for supporting a canopy.

Fig. 6 is a perspective view, showing the method of disassembling the skeleton frame.

Figs. 7 and 8 are detail perspective views showing the method of attaching the wheels to the frame when it is desired to use the apparatus as a portable bed or light ambulance.

Fig. 9 shows the means for supporting a curtain, or mosquito curtain for protecting the occupant against mosquitos or a waterproof covering for protecting the occupant against rain.

Fig. 10 shows a modified construction in

which the frame members are connected by a hinge joint to allow of folding together.

The framework of my improved apparatus, (see Figs. 2 and 3) may be formed of wood, but preferably of metallic tubing or any other suitable material, such as steel, duralumin, or the like. It consists of two side members, each of which comprises a straight central part a^1 b^1 and two straight end parts a^2 a^3 and b^2 b^3 , which when in use stand at obtuse angles with the respective central parts a^1 b^1 . These central parts a^1 b^1 are adapted to rest upon the ground and the end parts a^2 , a^3 and b^2 , b^3 of each side member are designed to incline at an angle with the vertical toward the corresponding parts of the other side member, and to be jointed thereto by any suitable means, thus forming a stable cradle capable of supporting from transverse bars D at the apices, without the addition of any struts, stays, ties or the like, a hammock or the like receptacle C, which may be suspended in such manner as to be well above the ground.

Each of the frame side members, is for the sake of easy portability, composed of several distinct pieces, see Fig. 5 adapted either to fit together easily and quickly by means of suitable couplings, or while remaining permanently connected, to open out and to fold up into a small space. As shown in Figs. 2 and 3 obtuse angled couplings a^4 are employed to connect the central parts a^1 b^1 respectively with the end parts a^2 , a^3 , b^2 , b^3 each coupling being preferably permanently fixed to one of the two parts it is adapted to connect, as shown in Fig. 5 while the other part may be inserted therein or withdrawn therefrom at pleasure. As shown in Fig. 9, the three parts a^1 a^2 a^3 are permanently connected by hinged joints a^6 , suitable stops or the like, such as a^5 being provided, limiting the angular rotation of the parts a^2 a^3 in one direction, so that when in use the three parts

may assume the proper positions relatively to one another, but nevertheless, permitting the said part to be folded together by rotation around the pivots in the opposite direction, so as to lie alongside one another in the smallest possible compass. Where hinged joints are thus employed, the parts a^2 and a^3 are preferably not in the same plane, so that when the frame member is folded up, the said parts may lie snugly alongside one another.

The hammock like receptacle C which may

be of canvas or other suitable material is attached to the transverse bars or rods D by means of cords e which are passed through eyelets c¹ c² in the ends of the receptacle C. The preferred method of attachment consists in attaching one end of the cord e to one of the end eyelets c² and passing the opposite end of the cord through a metal ring f, back through the adjacent eyelet c¹ again through the ring f and then through the central eyelets and similarly looping the same through the ring f¹ on the opposite side and finally attaching the free end of the cord e to the end eyelet c² on the opposite side. The rings f thus remain permanently attached to the cords and when it is desired to assemble the hammock it is merely necessary to slip the rings over the ends of the transverse rods D the ends of the latter being provided with slots d with which the rings engage, as shown in Figs. 1 and 4. When it is desired to stretch the canvas receptacle taut, for instance when the apparatus is to be used as a portable bed or ambulance, the looped portions e e¹ of the cord are slipped over the ends of the transverse rod D before the rings f are placed in the slots d.

The transverse rod or bar D has permanently secured thereto an acute angled coupling d² into which the upper ends of the parts a², a³, b², b³ of the frame are inserted. The coupling d² is also provided with a socket d³ into which is placed a rod g to the upper end of which the canopy, curtain or covering is attached, as shown in Figs. 1 and 5.

The canopy h shown in Figs. 1 and 5 is provided with pockets or the like h¹ at the corners at each end and a rod k is provided which engages at its ends in said pockets. The canopy is supported from the rods g, g by means of cords m and springs n, the cords of each being attached to opposite corners of the canopy, passed through a loop attached to one end of the spring n and through a ring o fixed to the center of the end of the canopy, back again through the loop of the spring and attached to a ring at the opposite corner of the canopy. To attach the canopy, it is merely necessary to engage hooks n¹ with the upper ends of the rods g, the springs and cords being permanently but adjustably mounted on the canopy.

When a rainproof covering as in Fig. 9 is to be attached, the rods g serve for attachment of a cord p extending through a hem or seam q in the center of the covering r. In this case the cord p is secured to the rods g g by tying and the ends of the covering are carried over the top of the rods g and laced together, as shown at r¹ in Fig. 9 by the occupant from the inside.

65 The method of attaching the wheels to

the framework is shown in Figs. 1, 7 and 8. As will be seen, the central side members a¹ b¹ have rigidly attached thereto lugs s the upstanding portions s¹ of which are formed with keyhole slots s². The wheels t are mounted loosely on an axle u the ends of which project slightly beyond the hubs of the wheels. The projecting ends of the axle are provided with an annular groove u¹. The lower portion of the key hole slots s² in each of the lugs s is of sufficient size to permit the end of the axle to pass therethrough, while the upper portion of said slot is of a width to receive the grooved portion of the axle only. To attach the wheels it is merely necessary to place the wheels loosely upon the ends of the axle and by slightly springing the central members a¹ b¹ of the frame apart, the ends of the axle may be engaged in the slots s². The lugs do not interfere with the use of the frame as a hammock or bed and the wheels can be easily and quickly detached in the matter of a few seconds.

By the construction above described my invention provides a frame for a sleeping apparatus possessing small weight and easy portability and which requires no struts or ties in use, and is capable of being erected or taken down and packed for transport in a very short time. The peculiar construction also has the advantage that it can be adapted for various purposes and for use under varying climatic conditions without necessitating any structural alterations whatever.

What I claim and desire to secure by Letters Patent of the United States of America is:—

1. A hammock, portable bed, or the like, comprising in combination, a metallic tubular frame formed of two side members, each consisting of a straight central part and two straight end parts connected thereto by obtuse angled couplings, the end parts of each side member being connected together by an acute angled coupling, a horizontal tubular member secured to and extending transversely on each side of each acute angled coupling, a hammock-like receptacle supported by cords from the extremities of said horizontal members, rods extending vertically from the center of said acute angled couplings, a covering supported above said hammock-like receptacle by cords attached to the upper ends of said rods, and means for maintaining the said covering taut and in a horizontal plane above said hammock-like receptacle.

2. A hammock, portable bed or the like, comprising in combination, a metallic tubular frame formed of two side members each consisting of a straight central part and two straight end parts connected thereto by obtuse angled couplings the end parts of each

side member being connected together by an acute angled coupling, a horizontal tubular member secured to and extending transversely on each side of each acute angled coupling, a hammock-like receptacle provided with eyelets at spaced intervals apart along each of its ends, cords passing through said eyelets, rings on said cords engaging slots in the extremities of said horizontal tubular members, so as to support the hammock-like receptacle therefrom, rods extending vertically from the center of said acute angled couplings, a covering above said receptacle supported from the upper end of said vertical rods by cords, and means for maintaining said covering taut above said receptacle, for the purposes set forth.

3. A hammock, sleeping apparatus, portable bed or the like, comprising a metallic tubular frame formed of two side members

each consisting of a straight central tube, two straight end tubes each having rigidly fixed thereto at one end obtuse angled couplings adapted to receive the ends of the straight central tubes, and horizontal tubular members each having rigidly fixed thereto equidistant from opposite ends, an acute angled coupling adapted to receive the ends of the straight end tubes of each side member, a hammock-like receptacle supported by cords from the extremities of said horizontal tubular members, rods extending vertically from said acute angled couplings, and a covering for said hammock-like receptacle supported by cords from the upper ends of said rods.

In testimony whereof, I have hereunto subscribed my name.

FRANK GODDARD.
